MOBILE ORNAMENT

Robert H. Hagey, Wilmette, Ill.

Application April 9, 1953, Serial No. 24,420

Term of patent 7 years

(Cl. D34—16)

To all whom it may concern:

Be it known that I, Robert H. Hagey, a citizen of the United States, residing at Wilmette, in the county of Cook and State of Illinois, have invented a new, original, and ornamental Design for Mobile Ornament, of which the following is a specification, reference being had to the accompanying drawing, forming a part thereof.

In the drawing:

The figure is a perspective view of a mobile ornament, showing my new design.

I claim:

The ornamental design for a mobile ornament, substantially as shown.

ROBERT H. HAGEY.
